M. D. ADLER

COIN RECEPACLE

Filed April 17, 1922

INVENTOR
MILTON D. ADLER
BY
Lewis J. Doolittle
ATTORNEY

UNITED STATES PATENT OFFICE.

MILTON D. ADLER, OF NEW YORK, N. Y.

COIN RECEPACLE.

Application filed April 17, 1922. Serial No. 553,890.

To all whom it may concern:

Be it known that I, MILTON D. ADLER, citizen of the United States, and resident of New York city, in the county of New York and State of New York, have invented certain new and useful Improvements in Coin Receptacles, of which the following is a specification.

This invention relates to coin containers or receptacles of the kind which may be conveniently carried in the pockets of a person's garments.

It is one object of this invention to provide a receptacle which can hold a large number of coins and yet not be bulky or of inconvenient size.

It is a further object of this invention to provide a receptacle which permits easy insertion and withdrawal of coins. A feature of this receptacle is that coins may be deposited without the actuation of operating mechanism, if desired, but from which the coins may not be drawn except upon suitable operation by the holder.

Still another object of this invention is the provision of an inexpensive, efficient, neat-appearing and highly-serviceable coin case.

Other objects and advantages will herein after appear.

In the accompanying drawings:

Fig. 1 is one form of coin receptacle embodying my invention.

Fig. 2 is a vertical cross-section through the device shown in Fig. 1.

Fig. 3 is a section taken on the line 3—3 of Fig. 2.

Fig. 4 is a section taken on the line 4—4 of Fig. 2.

Fig. 5 is a sectional view of a modified form of coin-controlling means.

Referring to Figs. 1 to 4 of the drawings, there is shown a coin receptacle comprising side walls 10 and 11 and a central partition 12 between and spaced from said side walls to form pockets on both sides of said partition. While the invention is herein described in connection with a receptacle having two pockets, it is to be understood that these pockets and the mechanism cooperating therewith are in all respects duplicates, and that a single pocket receptacle may be constructed in exactly the same manner as the two-pocket device. The latter, however, stores a larger number of coins, which is usually a desirable feature.

Said central partition is provided along its edges with laterally projected spacing flanges 15 and 16 (see Fig. 4) disposed on its edges to form spaces between said partition and said side walls to permit the coins to slide therein. The side walls are provided with various complementary flanges 17, 18 at those points where the flanges 15 and 16 are cut out to permit various operating mechanism (to be hereinafter described) to be mounted.

To permit insertion of coins, each pocket 22, 23, is provided with a slot 20, 21, respectively. These slots are formed in the respective flanges 15 and 16 adjacent diagonally opposed corners of the receptacle. To prevent falling out of the coins from the pockets there may be provided a stop member 25 normally projecting into the slot to close the same. Each stop member has fixed to its rear end one end of a stem member 27 having at its other end an operating member or finger piece 30 which projects outwardly through another longitudinal slot 32 in the edge of the partition 12, the stems being located in grooves 36 formed in the edges of the partition midway between the side walls of the receptacle, and connecting to lateral offsets such as 25' on the rear ends of the stop members. Springs 26 are provided in the grooves 36 and surround the stems 37 for holding said stop members normally in said slots to prevent discharge of coins.

In use, it will be understood that whenever coins are to be inserted or withdrawn from a pocket, the respective stop member is slid out of the slot by means of operating member 30, and against the action of spring 26. In order that coins may be inserted without actuating the operating member 30, the portion 25 of the stop member which projects into the slot may have its outer surface in the form of a cam 37, so that when the coin is inserted it will cam the stop member out of the slot to permit insertion of the coin. As soon as the coin has entered the pocket, spring 26 will restore the stop member to its normal position in the slot. In order that the coins within the pockets may be seen, there may be provided openings 35 in the side walls in register with the coins, but of smaller diameter.

In the modified form shown in Fig. 5 coins may be both inserted and withdrawn without actuation of an operating member,

and the latter may be dispensed with. The projecting stop portion 25 is provided in this case with both an outer cam surface 37 and an inner cam surface 40. The insertion of the coins will operate the stop member as hereinbefore described. By shaking the receptacle so that a coin operates against cam surface 40, the stop member will be cammed out of the slot to permit a coin to pass out. Ordinary handling of the coin case will not cause the coins to be discharged, since the cam is so shaped and the strength of spring 26 so adjusted that only a vigorous actuation of the case in the proper direction will serve to discharge the coins.

The above description is to be taken merely as illustrative of my invention, but it will be understood that various changes may be made within the scope of the annexed claims.

Claims:

1. A coin receptacle comprising side walls and a central partition spaced from said side walls by laterally projecting flanges at its edges extending therefrom in opposite directions at the ends and along a portion of each side, said side walls being provided with complementary flanges extending along a portion of each side and forming, with said partition flanges, slots for the insertion and removal of coins and recesses in which spring pressed stop members are positioned, and spring pressed stop members positioned and enclosed in said recesses and slidable longitudinally therein, said stop members normally projecting at one end partially into said slots and being provided with means for operating the same from the exterior of the receptacle to selectively slide the projecting end of either of said stop members out of said slot to permit a coin to be inserted or withdrawn from either side of said central partition.

2. A coin receptacle comprising side walls 45 and a central partition spaced from said side walls by laterally projecting flanges at its edges extending therefrom in opposite directions at the ends and along a portion of each side, said side walls being provided with complementary flanges extending along a portion of each side and forming with said partition flanges, slots for the insertion and removal of coins and recesses in which 50 spring pressed stop members are positioned, and spring pressed stop members positioned and enclosed in said recesses and slidable longitudinally therein, said stop members having one end normally projecting into said slots and formed with cam surfaces on the outer and inner surfaces thereof adapted to permit a coin to be inserted past the stop by engagement with the outer cam surface and removed by shaking the receptacle causing the coin to engage the inner cam surface of the stop member, the stop member automatically returning to its normal position after a coin has been inserted or removed.

3. A coin receptacle comprising a narrow flat casing of rectangular outline having a longitudinal partition located between and spaced from its side walls to provide a pair of coin chambers, said casing having coin slots formed in the edge wall thereof 70 adjacent diagonally opposed corners and leading into the respective chambers, stop members partially closing said slots and having lateral offsets at their rear ends, stems fixed to said offsets and located in recesses in said edge wall midway between the side walls of the casing, and expansion springs surrounding said stems.

Signed at New York city, in the county of New York and State of New York, this 85 14th day of April, A. D. 1922.

MILTON D. ADLER.
